DESIGN FOR A STORE DISPLAY FIXTURE

Edwin C. Dimling, Flushing, N. Y., assignor to Cluett, Peabody & Co., Inc., Troy, N. Y., a corporation of New York

Application July 27, 1946, Serial No. 132,013

Term of patent 14 years

(Cl. D80—11)

To all whom it may concern:

Be it known that I, Edwin C. Dimling, a citizen of the United States, residing at Flushing, Queens County, New York, have invented a new, original, and ornamental Design for Store Display Fixture, of which the following is a specification, reference being had to the accompanying drawing, forming part thereof.

In the drawing:

Fig. 1 is a perspective of a store display fixture showing my new design; and

Fig. 2 is a perspective of one of the trays forming a part of the fixture.

I claim:

The ornamental design for a store display fixture, substantially as shown.

EDWIN C. DIMLING.
